UNITED STATES PATENT OFFICE

2,274,395

LOCOMOTIVE

John Phillips Badenhausen, Philadelphia, Pa.

Application February 8, 1940, Serial No. 317,807

2 Claims. (Cl. 105—36)

This invention relates to locomotives and more particularly to power plants and driving units for locomotives.

In the locomotives which are now in use and which burn coal or oil the utilization of the heat available in the fuel is relatively inefficient. As a result the cost of fuel for operating the locomotive is excessive and the total fuel requirements of the railroad are much higher than is reasonable and proper.

With the steam locomotives now in use, also, it is necessary to carry a relatively large quantity of water to be supplied to the boiler, and at frequent intervals to replenish the water supply, either by stopping the train or by picking up water while running. By reason of the quality of the water thus used scale formation in the boiler tubes is a constant source of difficulties and the maintenance costs of the boiler are very high.

It is an object of the present invention to provide a locomotive and power plant therefor which will be efficient in its fuel consumption, in which the make up water required for steam generation will be relatively small in quantity and in which the quantity of fuel required will be greatly reduced.

It is a further object of the present invention to provide a power plant for locomotives in which the operating and maintenance costs will be greatly reduced.

It is a further object of the present invention to provide a locomotive which will have more power available for tractive effort for a given size and which will also have power available, preferably in the form of electrical energy, for use with the auxiliaries of the locomotive and in the train for lighting, heating, air conditioning, cooking and the like.

It is a further object of the present invention to provide a locomotive which will have a suitable booster for starting and for continuous driving.

Other objects of the present invention will be apparent from the annexed specification and claims.

The nature and characteristic features of the invention will be more readily understood from the following description, taken in connection with the accompanying drawing forming part hereof, in which:

Figure 1A is a diagrammatic longitudinal view of the front half of a locomotive unit involving the main features of the present invention, parts

being shown in section for purposes of illustration; and

Fig. 1B is a similar view of the rear half of the locomotive unit of the present invention.

It will, of course, be understood that the description and drawing herein contained are illustrative merely, and that various modifications and changes may be made in the structure disclosed without departing from the spirit of the invention.

Referring more particularly to the drawing in which a preferred embodiment of the invention is illustrated in diagrammatic form, the locomotive of the present invention is provided with the usual main frame 10. The frame 10 is preferably supported upon a front truck 11, front driving wheels 12, rear driving wheels 13, and a rear truck 14, although the use of the drivers as herein shown is merely illustrative. A tender 15 having a frame 16 and supported upon wheels 17 is coupled to the main frame 10 in any preferred manner.

The main frame 10 has mounted thereon a steam generator which may be of any preferred type. The steam generator preferably includes a boiler 18, a superheater 19, an economizer 20 and an air preheater 21. The boiler 18 is preferably made without rivets and without welding and with the tubes thereof large enough so as to be easily cleaned. It is also preferable that the tubes be short and set close together so that the fire box or combustion space is entirely enclosed within tube surfaces.

There is illustrated in my copending application for Letters Patent filed June 16, 1939, Serial No. 279,475, which issued January 14, 1941, as Patent No. 2,228,590, a steam generator of a type suitable for use in connection with the present invention.

As illustrated in the present application the boiler 18 preferably includes an upper longitudinally disposed steam and water drum 25 and a plurality of tubes 26 which extend from the boiler drum 25 and provide with the drum 25 the top of the combustion space or fire box. The tubes 26 also extend downwardly to provide the side walls of the combustion space or fire box and the tubes 26 are closely spaced so as to touch and provide an interior heating surface composed of tube surfaces. The lower ends of the tubes 26 are preferably connected to one or more headers 27 as desired.

A transverse wall 28 adjacent one end of the drum 25 is provided and has a suitable opening 29 therethrough for the introduction of the fuel

and preheated air. An upwardly extending wall or baffle 30 is provided near the other end of the boiler drum 25 and is preferably terminated below the drum 25 so that hot gaseous material can pass around the upper end thereof. A downwardly extending wall or baffle 31 is also provided and a screen composed of spaced down-comer tubes 32 is provided in the space between the side walls, the baffle 30 and the baffle 31 for the purpose of preventing cinders or solid burning fuel from being carried beyond the wall 31 and onto the tubes of the superheater 19 or the air preheater 20.

The size of the boiler will, of course, be dependent upon the capacity desired for the locomotive and the fire box may, if desired, range from approximately 18 feet to approximately 28 feet in length. The boiler is preferably of a character such that it will be capable of generating high pressure steam of the order of 700 to 800 pounds pressure, and with adequate provision for superheating the steam.

The superheater 19 is preferably provided in advance of the wall or baffle 31 and in the space between the side walls, the wall or baffle 31 and an upwardly extending wall or baffle 33. The superheater 19 is connected to the boiler drum 25 by means of a steam pipe 36. The superheater 19 is provided for increasing the quantity of heat carried by the steam, this heat being readily available in the combustion gases passing from the boiler 18. The superheater 19 has a steam main 37 connected to the outlet thereof for supplying the steam, as hereinafter pointed out.

A wall 38 is preferably provided in advance of the superheater 19 and in the space between the walls 33 and 38 and the side walls the economizer 20 is preferably located. The economizer 20 is provided for extracting further quantities of heat from the products of combustion passing from the fire box or combustion space. The economizer 20 is connected to the boiler drum 25 by the tubes 39 and feed water is supplied to the economizer 20 by the feed water supply pipe 40. The feed water supply pipe 40 has a control valve 41 therein.

The air preheater 21 is preferably disposed in advance of the economizer 20 and of the wall or baffle 38 for preheating the air supplied to the fire box or combustion space by extracting heat from the exhaust gases of combustion. The hot air outlet of the air heater 21 is preferably connected to the inlet 29 in the wall 28 by a duct 45 for supplying preheated air for combustion of the fuel.

An induced draft fan 46 is provided, preferably in advance of the air preheater 21, and is connected to the gas outlet of the preheater 21 for providing the proper pressure conditions within the fire box or combustion space of the boiler. The gases of combustion are preferably discharged by the induced draft fan 46 through the stack 47. The induced draft fan 46 may be driven in any desired manner, but is preferably actuated by an electric motor 48, the electrical energy being supplied thereto as hereinafter referred to.

The main frame 10 preferably also has mounted thereon on each side steam cylinders 50 of the customary type, together with the customary valve and valve mechanism 51 for controlling the admission of steam to the cylinders 50.

The piston rods 52 are also connected by con-

necting rods 53 to the drivers 12 in any desired manner for actuation of the locomotive.

The main frame 10 preferably also has mounted thereon a turbo-generator unit which includes 5 a high pressure steam turbine 55 directly connected to an electrical generator 56. The steam main 37 from the superheater 19 is connected to the inlet side of the high pressure steam turbine 55, a suitable control valve 57 being provided in the steam main 37 for controlling the admission of steam to the high pressure steam turbine 55.

The exhaust side of the steam turbine 55 is connected by a steam pipe 58 which extends forwardly to the control valve mechanism 51 for the steam cylinders 50 and the pressure of the steam from the turbine 55 is preferably of the order of 300 pounds, which pressure is now commonly used in steam locomotives. A control valve 59 is provided in the steam pipe 58.

A steam line 60 is also provided and is directly connected from the superheater 19 to the engine cylinders 50, an expansion valve and desuperheater 61 being provided for reducing the pressure and temperature of the steam supplied through the steam line 60 to the engine cylinders 50 to approximately that normally available at the exhaust of the steam turbine 55. The steam line 60 has a control valve 62 therein.

30 A control panel 65 upon which the various indicating and recording instruments are mounted is also preferably provided for easy access by the operator of the locomotive.

The tender 15 preferably has provided thereon 35 a fuel storage compartment 70 for the storage of coal, oil or any other preferred fuel. The fuel, if coal is used, may be supplied to the boiler by means of a stoker, but it is preferred, however, to use pulverized coal for fuel, since this 40 permits of the use of lower grades of coal which are procurable at reduced prices.

The tender 15 preferably also has mounted thereon one or more coal pulverizers 71 which may be of any preferred type for the pulverization 45 of the coal from the storage compartments 70. The pulverizers 71 are driven by motors 72 to which electric energy is supplied from the generator 56. The coal in pulverized form may be delivered through a fuel supply pipe 73 to the 50 boiler for combustion.

The tender 15 is also preferably provided with a water storage compartment 75 which is relatively small and ordinarily need only be sufficient for the limited make up required with the 55 locomotive of the present invention.

The tender 15 also has mounted thereon an air cooled condenser 77 which may be of any desired type, but preferably includes a large number of relatively small finned tubes 78, extending 60 between an upper distributing chamber 79 and a lower condensate collecting chamber 80.

A fan 81 is preferably also mounted on the tender 15 for directing air over the heat transfer surfaces of the condenser 77, and may be actuated by an electric motor 82 to which electric energy is supplied from the generator 56, as hereinafter pointed out. The air from the air condenser 77 is delivered therefrom through a cross duct 83 and discharged to the exterior of the 70 locomotive.

The exhaust side of the cylinders 50 is connected by a pipe 85 to the condenser 77 and the pressure of the steam at the exhaust side of the cylinders 50 will ordinarily lie in the range from 75 15 pounds to 50 pounds, dependent upon the speed

at which the locomotive is moving. A pipe 86 having a pump 87 and a control valve 88 therein is provided which extends from the condensate collecting chamber 80 to a tank 90, preferably also mounted on the tender 15.

A pipe 89 having a control valve 89a therein is also provided from the exhaust side of the turbine 55 to the condenser 77.

The tank 90 may serve as a storage tank and may also be utilized, if desired, as a feed water heater for the preliminary heating of the water therein. The tank 90 is connected by the feed pipe 40, having a pump 91 therein, to the economizer 20 for supplying water thereto and thus to the steam generator.

The water storage tank 90 is also preferably connected by a pipe 92 to the tank 75, a pump 93 being provided for delivering make up water from the water storage tank 75 to the tank 90, as required. A control valve 94 is provided in the pipe 92.

The generator 56 is utilized for supplying electric energy for operating the motors of the various auxiliaries, as well as for other purposes. Power leads 95 extend from the generator 56 to the control panel 65 and at the control panel 65 the electric energy is distributed to the auxiliaries. For this purpose, a line 96 is run to the motor 48 for the induced draft fan 46; a line 97 is run to the motor 82 for the condenser fan 81; and a line 98 is run to the motors 72 for the pulverizers 71.

A power line 100 is also provided which extends rearwardly for interconnection with a distribution line on the train for supplying electrical energy for lighting of the cars, for heating and air conditioning of the cars, for cooking in dining and club cars, and for other auxiliary power needs of the cars in the train.

The drivers 13 also have electric motors 101 connected thereto and power leads 102 extend from the control panel 65 to these motors. The tractive force available at the drivers 13 may be utilized for starting of the locomotive and may also be used while running in addition to the other tractive force available at the drivers 12.

The mode of operation of the locomotive of the present invention will now be pointed out.

Coal supplied from the fuel storage compartments 10 and pulverized by the pulverizers 71 is delivered through fuel supply pipes 73 and into the combustion space or fire box of the boiler 18. Preheated air is supplied through the duct 45 for introduction with the fuel. The heat released by the combustion generates steam in the tubes 26 lining the walls of the combustion space and in the drum 25. The hot gases of combustion pass over the top of the wall or baffle 30 and into contact with the downcomer tubes 32 where a portion of the heat in the gases is given up. The downcomer tubes 32, by reason of their staggered arrangement serve to prevent cinders and unconsumed fuel from being carried beyond this point. The hot gases then pass upwardly in contact with the tubes of the superheater 19 for the purpose of superheating the steam generated in the boiler. The hot gases pass around the upper part of the wall or baffle 33, and downwardly in contact with the tubes of the economizer 20, where they give up further portions of their heat. The hot gases then pass upwardly through the air heater 21 for the purpose of preheating the air for delivery through the duct 45 and are withdrawn at the upper part thereof by the induced draft fan 46. The gases are discharged from the stack 47.

The steam generated in the boiler 18 is collected in the drum 25 thereof and is delivered by the pipe 36 to the superheater 19 and from the superheater 19 the steam at high pressure and temperature is available for use.

While the locomotive is stationary steam is supplied to the steam turbine 55 through the pipe 37, is expanded in the turbine 55 and discharged on the exhaust side, and is conducted directly to the condenser 77 through the pipe 89, so that electric energy is available for the auxiliaries and for the other power needs heretofore referred to.

Under normal running conditions, however, the steam will be supplied to the turbine 55 and thence through the pipe 58 to the cylinder 50. The steam delivered to the cylinders 50 is expanded in the manner now well known in the art. From the exhaust side of the steam cylinders 50 the steam is delivered by the pipe 85 to the condenser 77. The pressure of the steam at the exhaust of the cylinders 50 will be dependent upon the speed at which the locomotive is running, and may range from approximately 15 pounds to approximately 50 pounds pressure.

The steam main 37 from the superheater 19 also has the branch pipe 60 connected thereto and to the steam cylinders 50, the reducing valve and desuperheater 61 being provided for reducing the temperature and pressure of the steam if for any reason it is desired to by-pass some or all of the steam around the turbine 55 and deliver the by-passed steam directly to the cylinders 50.

The steam delivered to the condenser 77 passes downwardly therein through the tubes 78 and is condensed.

The condensate, which is available in the collecting chamber 80 of the condenser 77, is returned through the pipe 86 by means of the pump 87 to the tank 90 and from the tank 90 is delivered by the pump 91, through the pipe 40, to the economizer 20. Any make up water which is required may be supplied from the water storage tank 75 by the pump 93 and the pipe 92 to the tank 90.

The energy available in the steam delivered to the cylinders 50 will be sufficient to provide a draw bar pull corresponding to that now available with steam locomotives. At the same time with the locomotive of the present invention large quantities of heat are available in addition and it is with this in view that the steam turbine 55 and the generator 56 driven thereby are employed.

When allowance is made for the power requirements of the auxiliaries, including the power supplied by the line 96 to the induced draft fan motor 48, the power supplied by the line 97 to the air condenser motor 82, and the power supplied by the line 98 to the motors 72 for the pulverizers 71, and the power required for driving the pumps and also the power supplied to the train through the power leads 100, large quantities of power are still available and these may be utilized for driving the motors 101 connected to the drivers 13.

By the combustion of fuel and the generation of steam, as herein proposed, together with the utilization of the energy available in the steam at high pressure and the utilization of the electric energy in the manner herein indicated, increased tractive power is available in the locomotive, while at the same time the fuel requirements are very sharply reduced. The circulation of the water in a closed circuit eliminates the ne-

cessity for carrying large quantities of water and the necessity for stopping the train or picking up water while running, is eliminated. Since the quantity of fuel required is greatly reduced savings will also result from the reduction of 5 the number of coaling stations required.

I claim:

1. In a locomotive, a closed steam and water cycle including a high pressure steam generator, said steam generator including a superheater and a boiler, a turbine for receiving high pressure superheated steam from said steam generator, driving cylinders connected to and receiving the exhaust at a pressure not in excess of 300 pounds from said turbine, an air cooled condenser for 10 directly receiving the exhaust steam from said cylinders at a pressure above atmospheric pressure and maintaining a back pressure of the order of 15 to 50 pounds at said cylinders, a bypass from the exhaust side of said turbine directly connected to said condenser, and means 15 for returning the condensate from said condenser to said boiler.

2. In a locomotive, the combination of a high pressure steam generator, a high pressure turbine actuated by steam from said steam generator and discharging steam at a pressure of the order of 300 pounds, high pressure steam cylinders for receiving the steam at said pressure from said turbine and for exhausting at a back pressure in the range of 15 to 50 pounds, an air cooled condenser directly connected to said cylinders and receiving the exhaust therefrom at a pressure above atmospheric for maintaining said back pressure in said cylinders, driving means for said locomotive actuated by said steam cylinders, an electric generator connected to said turbine, additional driving means for said locomotive electrically connected to said generator, means for supplying air for cooling said condenser, and means electrically connected to said generator for operating said supplying means.

JOHN PHILLIPS BADENHAUSEN.
